BED FOR BILLIARD TABLES AND THE LIKE

Filed Sept. 2, 1926

Fig. 1.

INVENTOR:
Edmund F. Hoskin,
By Sympathetic Acting
Attire

UNITED STATES PATENT OFFICE.

EDMUND F. HOSKIN, OF CHICAGO, ILLINOIS, ASSIGNOR TO WILLIAM A. SPINKS & COMPANY, OF CHICAGO, ILLINOIS, A CORPORATION OF ILLINOIS.

BED FOR BILLIARD TABLES AND THE LIKE.

Application filed September 2, 1926. Serial No. 133,194.

This invention relates to improvements in beds for billiard tables and the like.

Beds for tables of this character have heretofore generally been made of slabs of slate (usually three) placed edge to edge, and covered with cloth. Slate has been found to be well adapted for use immediately under the cloth as it can be made smooth, and is not easily dented or cracked by the fall of balls or impact from the end of a cue. It has become increasingly difficult and expensive, however, to procure slabs of slate of sufficient size and thickness for use for such purpose.

15 One of the features of my invention is the provision of a bed which has all the playing qualities of the ordinary solid slate bed but which can utilize small, irregularly shaped, and thin pieces of slate of the poorer grades. 20 My improved bed is also very strong and durable, probably more durable and stronger than a bed made out of solid slabs of slate.

Other features and advantages of my invention will appear more fully as I proceed 25 with my specification.

In that form of device embodying the features of my invention shown in the accompanying drawings, Fig. 1 is a top plan view of a table before showing a portion of the 30 cloth removed, Fig. 2 is a similar view on an enlarged scale of one corner showing a part of the slate surface or veneer removed, and Fig. 3 is a view taken as indicated by the line 3 of Fig. 2.

35 As shown in the drawings, my improved bed comprises, in general, a substantially rigid supporting material 10, on which is a veneer or surface of slate 11. The supporting bed 10 may be a single piece, the size of the entire table bed or several pieces may be used. For example, I have here shown three such pieces in order to make up the bed. The veneer or surface of slate 11 may be of one piece, but preferably will be made up 45 of many pieces as shown, in order to make use of the smaller irregularly shaped pieces of slate. The slate pieces are attached to the supporting bed 10 in any suitable manner as, for example, by cementing. I have found that a cement of shellac having powdered slate mixed therein serves the purpose. 12 indicates a cover such as the usual green cloth which is spread over the entire bed.

50 It will be seen that by using a rigid sup-

porting piece, or pieces as, for example, steel sheets 10 for the support, that a relatively thin slate veneer may be used. This permits the use of smaller and irregularly shaped pieces of slate, thus utilizing slate 60 of the poorer grades. Preferably the small pieces of slate 11, 11 are first cemented on the supporting piece 10, and then the entire top surfaced at once, thus making a smooth surface over all the pieces of slate on top. By 65 doing it this way, also, the bottom surfaces of the slate pieces do not have to be very smooth. In fact, if they are somewhat rough the cement will better hold them to the supporting part 10. Ordinarily, the bottom 70 surface of the pieces 11 may be left just as it is when the slate slabs come from the rough cutting machines. The edges, however, of the pieces must be cut square and the pieces nicely fitted together so that there 75 are no open cracks.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as 80 broadly as possible in view of the prior art.

What I claim as new, and desire to secure by Letters Patent, is:

1. In a bed for a table of the character described, the combination of a rigid flat supporting member having a veneer of slate on the upper surface thereof.

2. In a bed for a table of the character described, the combination of a rigid flat supporting member having a veneer of slate cemented to the upper surface thereof.

3. In a bed for a table of the character described, the combination of a rigid flat supporting member having a veneer of relatively smaller slate pieces on the upper surface thereof.

4. In a bed for a table of the character described, the combination of a rigid flat supporting member having a veneer of relatively smaller irregularly shaped slate pieces on the upper surface thereof.

5. In a bed for a table of the character described, the combination of a rigid flat supporting member having a veneer of relatively smaller irregularly shaped slate pieces

on the upper surface thereof, said slate pieces having their upper faces surfaced after being attached to the supporting member.

- 5 6. In a bed for a table of the character described, the combination of a rigid flat supporting member, and a plurality of relatively smaller irregularly shaped thin slate pieces supported on the upper surface of
10 said supporting member, said slate pieces having their edges fitted together to form a veneer of slate over the entire upper surface of said supporting member.

7. In a bed for a table of the character

described, the combination of a rigid flat 15 supporting member, and a plurality of relatively smaller irregularly shaped thin slate pieces supported on the upper surface of said supporting member, said slate pieces having their edges fitted together to form a 20 veneer of slate over the entire upper surface of said supporting member, and having their upper faces surfaced after being put in position on said supporting member.

In testimony whereof, I have hereunto set 25 my hand this 31st day of August, 1926.

EDMUND F. HOSKIN.
